E. A. CHRISTOPH

AMUSEMENT DEVICE

Filed Aug. 1, 1927.

Inventor

Edward A. Christoph

By Brown, Boettcher & Diemer,
Attys.

Patented Apr. 24, 1928.

UNITED STATES PATENT OFFICE.

EDWARD A. CHRISTOPH, OF CHICAGO, ILLINOIS.

AMUSEMENT DEVICE.

Application filed August 1, 1927. Serial No. 209,695.

This invention relates to an amusement device, particularly a toy pool or pocket billiard "table".

The purpose of the invention is to provide a simple and inexpensive structure which will serve the purpose quite as satisfactorily as the more expensive devices of this general type which have been on the market for a long time.

10 In accordance with my invention, the playing surface, instead of being an actual table top, is provided by simply a tablet which is adapted to be placed on any convenient plane surface when the game is to be played. This tablet is rimmed by a frame which provides the cushions and, together with the tablet, the pockets, the frame and tablet being preferably attached to each other by simple mechanical means.

20 In the accompanying drawing,

Fig. 1 is a plan view of the device of my invention;

Fig. 2 is a cross-sectional view, taken on plane of the line 2—2 of Fig. 1, looking in the direction indicated by the arrows; and

25 Fig. 3 is a partial cross-sectional view taken on plane of the line 3 of Fig. 1 and looking in the direction indicated by the arrows.

30 The plane surface of the device is provided by means of a tablet 4, of cardboard or wood or other similar material, with a covering 5 of felt laid thereon and extending over the peripheral edges and turned inwardly on the bottom, as shown in Figures 2 and 3, where it is conveniently pasted or glued to the tablet.

35 A frame 6, preferably of strip metal, surrounds the tablet, as shown, this frame being rectangular, except for the pocket formations to be described, and fitting closely upon the tablet. The straight sides of this frame carry appropriate cushions, the cushions in embodiment shown being provided by pieces 40 of rubber tubing 7 which surround the straight portions of the frame as indicated.

45 Accordingly pockets 8 and side pockets 9 are provided by looping the strip metal as indicated, true pockets being formed by the co-operation of the tablet 4, the thickness of which gives depth to the pocket. The tablet 4 is cut back slightly on an arc, as indicated at 10, 10, at each of the pockets, to simulate the regulation form of the pool or pocket billiard table, the cut back portion being chamfered as indicated at 11 in Figure 2.

When the structure is assembled, it is desirable, of course, that the tablet shall lay flat and, to this end, it is preferably arranged flush with the bottom of the assembled rim, as indicated in Figures 2 and 3. To maintain this relationship I provide pins 12 which pass through openings 13 in the rim and into the tablet 4, as indicated in Figure 3.

45 The assembled structure is laid upon a table, or other suitable plane and level surface, and the game then played on it in the usual way, the felt covering 5 forming the proper playing surface, the rubber tubing 7 forming appropriate cushions, and the co-operating tablet and loops of the frame forming appropriate pockets in which the balls may drop.

50 It will be obvious that changes and modifications can be made without departing from the spirit and scope of my invention as defined in the appended claims. The cushions, for instance, could be made of any resilient material suitably secured to the inside faces of the straight portions of the surrounding frame. Other means, than that shown, could be employed to secure the tablet and surrounding frame together. Indeed, the surrounding frame, instead of 55 actually having the tablet within it, might rest upon the upper surface thereof.

55 The appended claims are, accordingly, of varying scope, the broader ones covering structures so modified and the more limited ones covering the referred embodiment which I have specifically shown and described.

I claim:

1. In a device of the class described, a one-piece rectangular frame looped at intervals to form pockets, and rubber tubing covering the straight portions of said frame between said pockets.

2. In a device of the class described, a rectangular frame constructed of a single strip of metal looped at intervals to form corner and side pockets, rubber tubing covering the straight portions of said metal strip to form pockets, a felt covered tablet fitting in said frame and disposed flush with the bottom thereof, the periphery of said tablet being recessed and chamfered at said pockets, and pins extending through the straight portions of said frame and into said tablet.

3. In a device of the class described, a tablet forming a playing surface and a metal strip rimming said tablet, said strip being

looped at intervals away from said tablet, whereby the loops thus formed and the sides of the tablet at said loops cooperate to form pockets, and cushions on said strip between said loops.

4. In a device of the class described, a tablet forming a playing surface, and a metal strip surrounding said tablet and having its bottom substantially flush with the bottom of said tablet, said strips being

looped at intervals away from said tablet, whereby the loops thus formed and the sides of the tablet at said loops cooperate to form pockets, the surface upon which the assembled structure is laid acting as the bottom of said pockets.

In witness whereof, I hereunto subscribe my name this 27th day of July, 1927.

EDWARD A. CHRISTOPH.
